UNITED STATES PATENT OFFICE

RALPH J. MCKEE AND WILLIAM F. SCHEFFLER, OF CHICAGO, ILLINOIS, ASSIGNEES TO
CHICAGO MANUFACTURING & DISTRIBUTING COMPANY, OF CHICAGO, ILLINOIS, A
CORPORATION OF ILLINOIS

TRAFFIC MARKER

Application filed August 27, 1927. Serial No. 215,928.

This invention relates to street or road markers, or traffic guide buttons or markers.

One of the objects of the invention is the provision of a street marker that is provided with new and improved means for attaching the same to the street surface.

Another object of the invention is the provision of new and improved tread means on the surface of the marker for preventing the feet of pedestrians and horses from slipping when the marker is stepped on.

A further object of the invention is the provision of a new and improved marker, the exposed portion of which, when in position in the street, will be reinforced from beneath, and that will be water and frost proof.

Another object of the invention is the provision of a new and improved street marker that is cheap to manufacture, easily assembled and applied to the street surface, that is neat in appearance, efficient in use, and that is not likely to become loose, broken, or get out of order.

Other and further objects and advantages of the invention will appear from the following description taken in connection with the accompanying drawings, in which:

Fig. 1 is a plan view of the cap member of the marker;

Fig. 2 is a vertical section of the marker and a portion of the highway showing the marker in position therein;

Fig. 3 is a vertical section of a modified form of the device;

Fig. 4 is a vertical section of a modified form of cap;

Fig. 5 is a vertical section of a modified form of cap showing the attaching member secured therein; and

Fig. 6 is a plan view of a further modified form of the device.

Referring now to the drawings, in which similar reference characters designate the same parts throughout the description, the numeral 10 designates a highway, such as a street or road. The present invention is adapted to be secured in the highway to indicate traffic lines and the like, as is usual in the use of such devices. In marker de-

vices it is necessary that the caps or parts that are exposed be of such shape, form and quality of material that they will be conspicuous and will not become obscured by the dirt or refuse of the street. It is also necessary that the visible portion or cap of the marker be sufficiently reinforced that it will not become distorted by traffic passing over the same. It is also necessary that the parts be so constructed that water cannot get beneath the cap, otherwise, in cold weather, the freezing of the water will tend to loosen the marker.

In the form of the device selected to illustrate one embodiment of the invention the numeral 11 designates the cap or visible portion of the marker. This is preferably circular, although it is understood that it may be otherwise. In order that the marker shall stand sufficiently high above the plane of the highway to be plainly visible the cap 11 is cup-shaped or convex on its upper side. The peripheral edge of the cap 11 is provided with downwardly extending flanges 12 for engaging a groove in the pavement, as will presently appear.

As heretofore constructed, street markers are convex on their upper side, and for this reason pedestrians often slip and fall when stepping thereon. In order to avoid this difficulty the cap 11 is provided with upwardly extending bosses 13, the tops of which are substantially in a horizontal plane, whereby there will be no tendency to slip off the marker when a pedestrian steps thereon. In order to provide anti-slipping devices the bosses 13 may have holes 14 drilled or punched therein. The sharp edges 15 about the marginal outer ends of these holes will form means for preventing the foot from slipping from the marker.

Suitable means are provided for anchoring the marker to the pavement. As shown an attaching member 16 is provided for this purpose. The attaching member 16 may be secured to the cap 11 in any suitable manner. As shown in Fig. 2, the cap is provided with an axial opening 17 through which the upper end of the attaching member 16 is adapted to extend. The upper end portion of the

- supporting member 16 may be provided with an annular shoulder 18 for engaging the under side of the cap, which may be depressed about the opening 17, as shown at 19 in Fig. 2.
- 5 The upper end of the attaching member 16 is swaged or upset so as to completely fill the recess 21 formed by the depression 19, whereby a water-tight joint is formed between the attaching member 16 and the cap 11.
- 10 The lower end of the attaching member 16 may, if desired, be provided with an anchoring device. As shown, the member 16 at its lower end is enlarged to form the annular shoulder 22 and the convex surface 23.
- 15 In attaching the marker to the pavement of the highway the hole 24 is drilled for the reception of the attaching member 16. A groove 26 is formed concentric with said hole for receiving the flange 12. The hole 24 is then filled with asphalt, concrete, or the like, 25, in a plastic state. The attaching member 16 is then driven into the hole and the displaced plastic material will fill the cup-shaped space between the cap and the pavement, and the surplus will be extruded through the openings 15. The devices forced down until the flange 12 seats in the annular groove 26.
- After the plastic material 25 has become 30 set or hardened, the portion directly beneath the cap 11 will constitute a reinforcement for assisting in supporting said cap, and since it fills the entire space beneath the cap, it will render the entire installation water-proof.
- 35 The opening 24 and the groove 26 may be made deeper than the length of the attaching member 16 and the flange 12, respectively, especially if the opening 24 is to be filled with asphalt so as to permit a further depression 40 of the marker due to its constant use. Where the surface of the street is asphalt, it may not be necessary to provide a groove 26, since the flange 12 may be forced down into the surface by pressure.
- 45 The form of the device shown in Fig. 3 differs from that shown in Fig. 2 in that the attaching member 27 is rigidly attached to the cap 28. In this form of the device the cap 28 is provided with projections which 50 may be in the form of rivets 29 that may or may not have the openings corresponding to the openings 15 in the cap 11.
- The form of the device shown in Fig. 4 differs from that shown in Figs. 1 and 2 in 55 that the attaching member is dispensed with. In this construction the cap 31 is provided with the upwardly extending projections or bosses 32 and these bosses, as in the form shown in Fig. 1, are provided with openings 33 through the highest points thereof so that the edges of the openings will constitute anti-slipping means. In this construction the flange 34 may be considerably extended over the construction shown in Fig. 1. The flange 60 34 may be driven into the surface of the street

or pavement if the surfacing material is asphalt or wooden blocks or the like. If the surface of the pavement is concrete a groove is provided for the reception of the flange 34 and in applying the device the cap is filled 70 with suitable material in plastic state, such as asphalt, mixture of asphalt and sand, or concrete or the like, and the cap is forced into position, causing the material to extrude through the openings 33.

75 The form of construction shown in Fig. 5 differs from that shown in Fig. 1 in the means for attaching the attaching member 35 to the cap 36. In this form the upper end of the attaching member 35 is upset as 80 at 37, forming the shoulder 38 against which the lower downturned edge 39 of the opening 41 in the cap 36 is adapted to abut. The upper end of the member 35 is then upset or swaged to make a water-tight joint and hold 85 the parts in assembled relation.

The form shown in Fig. 6 differs from that shown in Fig. 1 in that the projections 48 on the cap 49 are of angular form. These projections may, if desired, be provided with 90 openings corresponding to the openings 15 in the projections 13 for constituting anti-slipping devices. The attaching member may have its head 42 provided with studs or projections 43 for constituting anti-slip- 95 ping devices.

It is understood that in all these forms the cap is to be made from rust-proof material, and preferably from material that will reflect the light sufficiently to be distinctive. 100 The caps may be made from monel or any other bright, rust-proof metal.

While the cap members may be provided with the projections 13 without having the openings 15, it is preferred that these openings be employed as they will constitute vents through which the filler material for the holes 24, such as tar, asphalt, concrete and the like, may escape when the device is driven or pressed into position in the pavement.

110 Each of the projections 13 constitutes a reflecting surface for reflecting the light, and consequently each cap will reflect a great amount of light, while at the same time the reflected light will be more or less broken up 115 or diffused, whereby the composite reflection will not be objectionable to the observer.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

120 We claim as our invention:

1. A traffic marker comprising a circular cap member curved on its upper surface and having its peripheral edge turned vertically downward for engaging a circular groove in 130

the pavement, and a plurality of circular projections convex on their upper surfaces and provided with openings therethrough arranged in a circle about the vertical axis of said cap, the upper surfaces of said projections forming a horizontal tread.

2. A traffic marker comprising a cap member having an upper dome-shaped surface and provided with upwardly extending projections on said surface for forming a horizontal tread on said marker, and an attaching member rigidly secured to said cap member axially thereof.

10 3. A traffic marker comprising a cap member having an upper dome-shaped surface and a comparatively narrow depending peripheral flange adapted to engage in a groove in the surface of the highway, and a plurality of upwardly extending projections on said dome, the upper surfaces of said projections forming a horizontal tread over the upper surface of said dome.

15 4. A traffic marker comprising a cap member having a dome-shaped surface, a plurality of projections extending upwardly from said surface, the upper surface of said projections being in a plane at a right angle to the axis of said dome-shaped surface and depending means for securing said marker in operative position in the surface of a highway.

20 In testimony whereof we affix our signatures.

RALPH J. MCKEE.
